UNITED STATES PATENT OFFICE

150,130

DESIGN FOR A WALL PLAQUE

Peggy T. Gordon, Los Angeles, Calif.

Application June 5, 1946, Serial No. 130,417

Term of patent 3½ years

(Cl. D33—3)

To all whom it may concern:

Be it known that I, Peggy T. Gordon, a citizen of the United States of America and a resident of the city of Los Angeles, in the county of Los Angeles and State of California, have invented a new, original, and ornamental Design for Wall Plaque, of which the following is a specification, reference being had to the accompanying drawings, forming part thereof.

In the drawings:

The opposite side of Figure 2 is substantially the same as that shown in Figure 2.

The rear of the plaque is plain.

I claim:

The ornamental design for a wall plaque, substantially as shown and described.

PEGGY T. GORDON.
